DOMESTIC SPRINKLER SYSTEM

John B. Coleman, Providence, R. I., assignor to
 General Fire Extinguisher Company, Providence, R. I., a corporation of Delaware

Application June 20, 1932, Serial No. 618,265

2 Claims. (Cl. 137—78)

This invention relates to improvements in domestic sprinkler systems. More especially it has to do with an automatic system particularly designed for home use and so fabricated and supplied that the ordinary house dweller can readily install it.

The protective value and effectiveness of automatic sprinkler systems have long been recognized and such systems are regularly installed in factories, office buildings, hotels, schools, churches, club houses and other buildings of appreciable size. Large corporations have grown up whose business is primarily concerned with the installation of such systems in these very sizable risks. The system as generally known involves a large footage of pipes of graduated sizes, with numerous T's, elbows, couplings, unions, pipe hangers, sprinkler heads, dry pipe valves, alarm valves, gate valves and many other devices and incidental fittings. The pipe and fittings are sent to the risk and a corps of men then proceed to cut the pipe into proper lengths, thread it, install it and attach the various valves and fittings. These men are skilled workmen and so a very appreciable cost of the finished systems now in common use is the labor cost of installation. If a home owner desires such a system, even on a much smaller scale, the cost of having it installed in his house is well-nigh prohibitive, especially when all he needs is a few sprinkler heads arranged to protect some small but particularly dangerous hazard.

For example, the space under the cellar stairs lends itself most conveniently to the temporary storage of waste, and it is usually occupied by barrels and boxes of trash, to say nothing of the dangerous accumulation of old newspapers which are likely at any time to cause spontaneous combustion. Or the attic, around the chimney, is also a favorite collecting spot for things which may prove highly inflammable, especially if the chimney itself becomes defective as chimneys are wont to do. And in the modern home where the family automobile occupies a room of its own in the basement the gradual accumulation of grease and oil, to say nothing of discarded cleaning cloths, results in a fire hazard that can not be lightly disregarded even though supposedly fire-proof walls and barriers are provided. To install the usual type of automatic sprinkler system in these all too common places of fire danger is, as before stated, an expensive undertaking and one usually deemed a luxury that can not be afforded.

It is the principal object of this invention to provide a system that can be purchased by the home owner at a small cost and which he can install himself with hardly more than an ordinary monkey wrench and hammer as his tools. 5 It is a feature of the system that parts or sections can be assembled at the place of manufacture and yet this system as a whole can be shipped in a generally dismantled but compact condition to the ultimate user. It is a further 10 feature that each such factory assembled section is so arranged and constructed that it can be easily, but only correctly, connected to another similar section or to a different section which comprises a novel fitting that constitutes a shut- 15 off valve, an alarm valve and a test valve all in one unit. Such a system can be unpacked and quickly installed without the cost of skilled labor; it is adaptable for protecting spaces of varying extent and location and because of this and 20 its "fool-proof" features, the inexperienced house dweller need not worry about the fuss and bother and high cost of installation. For a modest expenditure with the simple equipment herein disclosed he can effectively protect his home and 25 dear ones against the greatest fire menace in his house.

The best mode in which I have contemplated applying the principles of my invention is shown in the accompanying drawings but these are to 30 be taken as merely illustrative and it is intended to cover by suitable expression in the appended claims whatever features of patentable novelty exist in the invention disclosed.

In the accompanying drawings: 35

Figure 1 is a perspective showing a typical installation of a system embodying the present invention;

Figure 2 is a somewhat diagrammatic showing 40 of a system;

Figure 3 is a side elevation of the valve unit with the detachable cover removed;

Figure 4 is a plan of the unit with the cover and top nut removed;

Figure 5 is another elevation of this unit on 45 line 5—5 of Figure 4;

Figure 6 is a view showing the section of the system which connects with the valve unit and another section attached thereto;

Figure 7 is an elevation of one of the compression fittings with sprinkler attached and a cap nut for closing the end; and

Figure 8 is a view in section showing a plug for closing the end of a pipe.

Referring more particularly to the drawings, 55

Figure 1 suggests how the system might be installed in a modern cellar, part of which serves as a garage. The system is connected to the domestic water supply pipe 1, preferably near the meter 2. An ordinary T fitting 3 can be inserted in this line and a nipple 4 added to which the valve unit 5 may be attached by simply threading it on the nipple and turning it until tight.

10 The inlet end of this unit is provided with internal threads 6 to receive the nipple 4, and its outlet has a threaded stem 7 adapted to receive a so-called section of the system. This particular section has a piece of bendable pipe 8 permanently connected at one end to a compression fitting 9 either by soldering or brazing or the like. A coupling nut 10 is slipped on this piece of pipe and then its free end 8a is flared to fit the tapered seat 7a on the exposed stem of the valve unit. The 15 section is thus fabricated at the place of manufacture and all the house owner has to do is place the flared end 8a of the pipe against the tapered seat 7a on the valve unit, engage the nut 10 with the threads on the stem and tighten the 20 nut with a monkey wrench.

25 The compression fitting 9 just described has another pipe 11 permanently connected to it on one end and a threaded stem 12 with taper seat 12a at the other end. The stem and the pipe last mentioned are of different size from the piece of pipe 8 which connects with the valve unit, thus insuring that the proper piece of pipe leading from the fitting will be secured to the unit.

30 The remainder of the system comprises one or more sections each of which consists of a length of bendable metal pipe 11, a compression fitting 13 with inserted automatic sprinkler head 14 and a compression nut 15. One end of the pipe 11 is permanently secured in the fitting and its other 35 end 11a flared, after the nut 15 has been slipped over it. This, it is to be understood, is all done before the section leaves the manufacturer. When received by the ultimate user, he has only to place the flared end 11a of the pipe on the seat 13a of the fitting heretofore described and set up the compression nut 15. The pipe is then bent to bring the sprinkler head where desired, the latter being positioned either above the fitting as shown at A in Figure 2 or pendent from it as at B in Figure 2. Another section is now attached to this fitting, and still other sections added until as many 40 sprinklers are provided as the hazard requires. The final section is attached to pipe 11 of the fitting first of all mentioned this pipe having a flared end 11a and nut 15. Thus a loop of distributing or feed pipe is made for the several sprinklers. This "loop" is not an essential arrangement, as the sections can extend to any desired point and have the stem end of the last fitting closed by a 45 cap nut 16, such as is shown in Figure 7, or the pipe may be cut off near a fitting, its new end flared and closed by a plug 16' to which the nut 15 is attached as shown in Figure 8.

50 The pipe, being bendable, can be easily passed around beams or other timbers, under the stairs or placed anywhere a fire hazard exists. If the pipe of a section is longer than needed, part of it may be cut off and its new end flared and if a fitting happens to come where no sprinkler is desired the latter can be removed and a plug inserted in its place. The several nuts can be made tight with a monkey wrench and the pipe held in place with clips which can be anchored to the 55 ceiling or beams by nails.

55 When the user has thus installed the fittings

and thus connected the pipe or tubing he returns to the valve unit and opens the valve, it being assumed of course that after attaching this unit to the domestic line he has closed the valve of the unit and opened the main supply valve 17 of the 5 house line.

The unit 5 has a clapper 18 (see Figure 5) which seats by gravity, when no flow is occurring and which can be positively seated against the supply pressure by a "shut-off" stem 19 that extends outside the casing 20 and has a hand wheel 21 for turning it in or out, the stem being threaded in the casing and suitably packed to avoid leakage.

10 The axle 22 of the clapper extends outside the water way and has an arm 22a attached thereto which carries a "Mercoid" switch 23 consisting of a glass bulb containing a proper charge of mercury. Inside the bulb are exposed ends of wires 24, 25 which are adapted to be connected by the 15 mercury when the bulb is tilted. This tilted position of the bulb (shown in dotted outline in Figure 3) occurs whenever the clapper is lifted from its seat, as by the flow resulting from the opening of a sprinkler head. The wires 24, 25 are light and 20 very flexible and are connected to binding posts 26, 27 from which extend wires 28, 29 to a suitable source of electric current 30 and to an alarm 31 located where desired in the house. Upon the occurrence of a fire with opening of one or more 25 heads and consequent flow of water through the valve unit an alarm is thus given indicating that this system is in action.

30 After the fire is out, the clapper is seated by the hand-operated stem thus shutting off the 35 flow. The opened heads are removed and new ones screwed into the fittings thus making the loop tight again. The stem is then turned outward and the system is again ready to respond if the need arises.

40 In order to test the alarm a plug 31 in the base of the valve unit may be removed. This permits flow comparable to that caused by the opening of a sprinkler and will result in the clapper being lifted and an alarm sounded. If the clapper is held to its seat the plug may likewise be removed to drain water from the system.

45 While the installation shown in Figure 1 is a typical one, it is obvious that the system can be adapted to fit any location whatever its shape. 50 The pipe is readily bendable, the couplings easily made and because of the difference in size of some of the connections, the system can only be put together in the proper manner. All this makes it feasible and practicable for the home owner 55 to protect his family and property from fire hazards at a very moderate expense.

55 I claim:

1. Distributing piping for a domestic sprinkler installation comprising, in combination, a T-coupling with an inlet adapted to be connected to a domestic water supply and having two outlets of different size from said inlet; a piece of bendable pipe attached to one outlet; a coupling nut on said piece of pipe at the end remote from the 60 T-coupling; and a series of connected sections forming a loop extending from said piece of pipe to the other outlet of said T-coupling; each of 65 said sections comprising a piece of bendable pipe, a fitting at one end thereof, a coupling nut at the other end thereof; each fitting having an opening with external threads adapted to cooperate with a coupling nut to connect said fitting to an adjacent piece of bendable pipe, and an opening 70 adapted to receive a sprinkler head; the said 75

T-coupling and said sections being so organized as to be assembled in a predetermined sequence to form the said loop.

2. Distributing piping for a domestic sprinkler installation comprising, in combination, a T-coupling having an inlet adapted to be connected to a domestic water supply, and having two-outlets of a different size from said inlet with external threads on one of them; and means constituting a distributing loop between said outlets; said means comprising a piece of bendable pipe attached to one outlet of the T-coupling; a coupling nut on said piece of pipe at the end remote from
- the T-coupling; a fitting having an externally threaded stem engaged by said coupling nut to connect said piece of pipe and fitting together, an opening adapted to receive a sprinkler head, and another opening; another piece of bendable pipe attached to said other opening; and a coupling nut on said other piece of pipe at the remote end from said fitting adapted to engage the external threads on the T-coupling and thereby connect the other bendable pipe thereto and complete the loop. 5
- 10

JOHN B. COLEMAN.
